HYDROPNEUMATIC MASSAGER

Leon Josef Steinberg, Baltimore, Md.

Application October 15, 1951, Serial No. 251,297

1 Claim. (Cl. 4—180)

1

This invention relates to massaging apparatus and more particularly to a portable type of hydropneumatic therapeutic unit adapted for use in connection with a bath or its equivalent, and a shower device or water service.

The customary method of massaging the body of an individual requires the use of mechanical devices applied exteriorly to the person, and is more or less radical in its operation. This class of operation is not applicable in many instances where the situation requires less strenuous application. In other instances water is applied from special nozzles under pressure directly against the body. This invention employs an arrangement that applies water, but not alone. The water under pressure is combined with air sucked in by an injection process, so that when it impinges against the body of an individual it acts with a cushioning action. This is due to the disseminated distribution of the air bubbles throughout the ejected stream of water from the orifice of the invention. The combined water and air hit directly on the body of the patient or pass into the water filling the bath, and stir it up around him.

The invention has for an object to provide a new and improved massaging unit that will avoid one or more of the disadvantages and limitations of the prior art.

Another object of the invention is to provide a new and improved massaging unit that will employ a mixture of air and water for its massaging action.

A further object of the invention is to provide a new and improved massaging unit of a portable nature that can be readily adjusted to a position on the walls of a bath and the incidental shower equipment installed therewith.

An additional object of the invention to facilitate bubbling action in the bath if bubble ingredients are used.

Other objects of the invention will be apparent as it is more completely detailed.

For an illustration of the invention, its principles and operation, reference is made to the accompanying drawings. These drawings indicate a particular form of the invention by way of example, not of limitation, and are explained in the following description. This description portrays the construction presented and indicates the features that are conspicuously inherent in it. The claim is also appended to comprehend the scope of the invention.

In the drawings:

Figure 1 is a view in perspective of a hydro-

2

pneumatic massage unit embodying this invention; without a nozzle attachment;

Figure 2 is a side elevation of the nozzle block used in this embodiment;

Figure 3 is a sectional detail of the corner section of the nozzle block where the water and air ducts meet in a common orifice to discharge together in a combined stream of water with air entrapped in it, with a nozzle indicated in dotted outline; and

Figure 4 shows two preferred types of nozzles mounted on the nozzle block and partly in section to indicate the manner of attaching them in place when used.

Similar reference numerals pertain to the same parts throughout the drawings.

In this particular form, a clamp is employed for attachment to the upper edge portion of a bath tub 10. To do so the clamp has an inverted U-shaped structure with downward front and rear parallel walls 11 and 12 respectively and a joining web 13. From the upper surface of the web 13 extends an inverted L-shaped bracket 14. This bracket has an elongated slot 17 passing vertically through its curved upper arm 18 in which a post 15 extends to a position below or adjacent to the level of the clamp walls. This post 15 is adjustably held in the arcuate bracket arm 18 by means of a washer with nuts 16 threadably positioned on it, above and below the horizontal arcuate arm 18 of the bracket. At the same time, the post can be axially rotated in the slot or tilted to an angle with the vertical plane. This provides considerable flexibility to the positioning of the post and the parts supported on it. An adjustable clamp screw 19 threadably passing through the wall 11 is tightened against the bath 10 to make it hold securely. In addition it has an adjustable pad 21 on its end to enable it to fit properly against the bath tub, and a wheel handle 20 to tighten it.

A nozzle block 22 preferably of rectangular contour is attached to the post 15 by means of lugs 23 of sleeve form arranged to slide along the post. Set screws 24 are provided in the lugs 23 to fasten them to the post in any longitudinal position selected for the block as well as for axial rotation. The block 22 is provided with a pair of ducts extending longitudinally therethrough, one of which is an air channel 25 while the other is a water channel 26. They terminate adjacent each other at an ejector orifice 27 adjacent the bottom of the block and the angular plane 28 left by the lack of a corner at this portion of the block. The ducts 25 and 26 meet

at this location together, disposed in such relation to one another as to afford an ejector action. The open end of the air duct at the top surface 29 of the block 22 is preferably flush. The water duct 26 has a water connection and coupling 31 connected with it and fed by a flexible hose 30. The hose 30 is long enough to reach an adjacent hot and cold shower head or nearby faucet and has the necessary attachment 32 to hold it against the water pressure to the head or faucet. The coupling 31 is preferably located at the corner opposite to that of the open end of the air duct. When the water passes through the water duct under pressure and crosses the lower open end of the air duct, it draws in the air and mixes intimately with the latter. The water mixed with air flows in a stream into the water in the bath and stirs the latter. In some instances the block can be placed adjacent the body of the user and the water and air squirted directly against him. The water may be varied from hot to cold depending on the purpose for which it is to be used at the moment. The use of nozzles on the block at the orifice is optional, depending on circumstances.

The purpose of the unit and its distribution of the mixed air and water is for the treatment of individuals by hydro-pneumatic therapy. Because of the appreciable capacity of water for absorbing heat and of its slow cooling, it is a valuable medium for applying heat or absorbing same. Its temperature can be kept under control and measured readily. The device is particularly used in the treatment of arthritis, sprains, local pains and aches where a moist heat and massage are desirable.

On the angular plane 28 a corner piece 34 is fastened by screws 41 to form an extension. The corner piece is drilled and tapped for a nozzle 35, which has a single hole 37 through it for the stream of water and air to project. A screen nozzle 36 may also be employed instead, if the conditions make it desirable. The nozzles are made replaceable by providing hollow screw threaded stems 38 extending from them at the back. The placing of the corner piece 34 on the block covers the orifice 27 and leaves a recess over it to direct the water into the stem 38 which in turn through its interior passage carries the water to the nozzle to be sprayed by the latter.

The combined action of the heat and the gentle swirling mechanical action produced by the mixed air and water inflow, as well as, the softening effect of the whirling water of the bath about the body, soon produces a noticeable effect. After fifteen minutes the skin and flesh become pink and warm, and the circulation of blood and body fluids in the vicinity of application is promoted. The handle 33, mounted on the nozzle block is intended for use of the operator when he wants to position or adjust the unit.

The device is simple in construction, and is considerably more compact than the equipment previously used for similar purposes. It is portable, and can be handled by the average indi- 65

vidual with ease. It can be adjusted vertically or axially to suit his needs all without extensive instruction or attention. It can be made available at an economical cost, whereas the conventional equipment used in hospitals would be a prohibitive expense to the average patient. There is practically nothing to get out of order and the structure of the device is such that it will have a useful life for a long period. There are no moving parts to get out of order. It can be made of attractive design and materials and when not in use it may be packed away in a small space.

While but one general form of the invention is shown in the drawings and described in the specification, it is not desired to limit this application for patent to this particular form, as it is appreciated that other forms of construction could be made that would use the same principles and come within the scope of the appended claim.

Having thus described the invention, what is claimed is:

A hydrotherapy apparatus, usable in combination with a bath tub, comprising a portable block, a handle secured to said block on one face thereof, said block having an oblique face at a corner thereof opposed to the location of the handle whereby said block may be manipulated by means of the handle to position the oblique face towards any selected direction, said block having a water passage therethrough connectible at one end to a source of water pressure, the opposite end of said passage having a port opening flush with the oblique face, said block also having an air passage having a port opening at one end flush with the upper face of the block and said air passage having its opposite end provided with a port opening flush with the oblique face and juxtaposed to the port opening of the water passage whereby water issuing through the water passage sucks air through the air passage to be mixed with the water, angularly adjustable means for securing said block on the rim of the bath tub following the positioning of the block by means of the handle, and a removable nozzle connectible to the oblique face at the point of issuance of the aforesaid water and air passages.
